Primary Examiner — Keli L Hill*Assistant Examiner* — Harold E Blackwell, II(74) Attorney, Agent, or Firm — Muncy, Geissler, Olds & Lowe, P.C.(57) CLAIM

The ornamental design for a charging cabinet, as shown and described.

DESCRIPTION

FIG. 1 is a perspective view of a charging cabinet showing my design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view of a charging cabinet showing my design.

The broken lines in the drawings depict portions of the charging cabinet that form no part of the claimed design.
